(57) CLAIM

The ornamental design for a wireless speaker system with tablet stand, as shown.

DESCRIPTION

FIG. 1 is a front perspective view of the wireless speaker system with tablet stand.

FIG. 2 is a front elevational view thereof.

FIG. 3 is a side elevational view thereof.

FIG. 4 is a rear elevational view thereof.

FIG. 5 is a top plan view thereof; and,

FIG. 6 is a bottom plan view thereof.

The broken lines are for illustrative purpose only and form no part of the claimed design.
